UNITED STATES PATENT OFFICE.

FRANK A. SEYMOUR, OF MADELIA, MINNESOTA.

PROTECTOR FOR BRUSHES.

Application filed March 26, 1921. Serial No. 455,878.

To all whom it may concern:

Be it known that I, FRANK A. SEYMOUR, a citizen of the United States, residing at Madelia, in the county of Watonwan and State

60

of Minnesota, have invented certain new and useful Improvements in Protectors for Brushes, of which the following is a specification, reference being had to the accompanying drawings.

10 The invention has for its purpose the provision of an improved protector for brushes in general, paint brushes in particular, the aim being to provide a protector, for holding the bristles together and in shape, particularly after the brush has been cleaned of the paint.

Very often after cleaning a brush of paint, and the bristles are allowed to dry, they tend to spread, so that when the brush is again used, certain of the bristles project from the body of the bristles, thereby tending to apply the paint irregularly, especially when it is desired to apply a certain color of paint adjacent to another color of paint. In fact 25 in applying one color of paint adjacent another color which may be dried or wet, the bristles have been allowed to improperly spread, or extend beyond the body of the bristles, the paint previously applied may 30 become smeared or covered with another color of paint, therefore it is an essential purpose to avoid this, by providing a protector to hold the bristles together, while they are drying, namely after they are 35 cleaned of the paint.

Still another purpose consists in the provision of a protector or holder for the paint brush comprising a mesh work body for the reception of the bristle portion of the brush, 40 and a part of the body or wood portion of the brush, there being a mesh work cover, in combination with means passing through the handle of the brush, and connecting projections of the body and the cover of the 45 holder or protector, in order to hold the brush in position in the holder, with the bristles in compact form.

It is a further purpose to provide a protector or holder which is slightly tapered, in 50 order to insure holding the bristles in proper form.

While the design and construction at present illustrated and set forth is deemed preferable, it is obvious that as a result of a reduction of the invention to a more practical 55 form for commercial purposes, the invention

may be susceptible of changes, and the right to these changes is claimed, provided they are comprehended within the scope of what is claimed.

The invention comprises further features and combination of parts, as will be herein-after set forth, shown in the drawings and claimed.

In the drawings:

Figure 1 is a view in perspective showing the improved protector or holder as applied to a brush, though it is obvious that a holder may be constructed for any other character of brush.

Figure 2 is a sectional view on line 2—2 of Figure 1, showing how the protector sections are hingedly united, and how the protector is connected to the handle of the brush detachably.

Figure 3 is a plan view of the brush showing the two sections thereof opened.

Figure 4 is a cross sectional view on line 4—4 of Figure 1.

Referring more especially to the drawings, 1 designates the body section of the protector or holder, and 2 the closure or cover section of the protector or holder. These sections are constructed from wire mesh or fabric, preferably of the gauge disclosed, though it is obvious that any gauge of wire fabric may be employed. The body section is flanged on three of its sides, there being a sheet metal binding 4 clamped to the margin of the flange 3, which extends about the three sides of the body section.

The body and cover sections of the protector are correspondingly tapered viewing the protector in plan and side elevation, and extending about the margin of the cover section on three of its edge portions is a sheet metal binding 5. The bindings on both sections are bent upon themselves, therefore are U-shaped in cross section, to hold and protect the wire fabric. The bindings 95 on the smaller ends of the two sections have alternate cut away portions 6, thereby causing to be formed alternate projecting sleeves 7, which engage the corresponding alternate cut away portions, there being a hinge pin 100 100 extending axially through the sleeves, thereby hingedly connecting the body and cover sections. A projection 9 is carried by the body section, and extends in a direction parallel with the handle 10 of the paint brush. This projection is composed from

single sheet metal bent upon itself as at 110

11, and for substantially half its length the metal on its bent portion is cut, thereby causing to be formed two projecting arms 12, which straddle the wire fabric or mesh work. These arms are riveted at 13 to the mesh work, and soldered or otherwise connected at 14 to the edge of the mesh work. A lateral pin 15 is carried by the projection, and when the holder or protector is applied to the brush, the lateral pin engages through a transverse opening 16 in the handle of the brush. This lateral pin 15 is provided with a series of notches 17, and is designed to engage through an opening 18 in a projection 19, which is carried by the cover section, there being a latch 20 to engage any one of the notches in the pin to hold the body section and cover section in engagement with the brush. The latch 20 is pivoted on the projection 19, and its end edge, which is arcuate in contour, engages any one of the notches. The latch is provided with a flange 21 to engage the edge of the projection 19, to limit the movement of the latch when engaging the notches. The latch is also provided with an upwardly projecting flange 22 on its opposite edge, to be engaged by the thumb or finger, for moving the flange out of engagement with the notches. The projection 19 is composed from a single sheet metal bent longitudinally upon itself as at 23, there being arms 24 (caused to be formed by cutting the sheet metal where it is bent for substantially half the length of the projection) straddling the cover section, and riveted and soldered to the cover section as at 25 and 26.

It is obvious that a holder or protector of this character may be constructed for any character of brush, and furthermore the two sections may be constructed of any suitable wire fabric or mesh work, or of any other suitable material.

The invention having been set forth, what is claimed as being useful is:

1. In a protector or holder for brushes, the combination with a body section having a marginal flange on three of its edges, a

cover section hingedly connected to the body section, a pair of projections carried by the body and cover sections and adapted to be disposed in parallelism when the protector is applied to the brush, and means carried by one projection and passing through the handle of the brush and being detachably connected to the other projection for holding the brush in the protector.

2. The combination with a body section, of a cover section hingedly connected thereto, projections carried by the two sections and adapted to assume parallel positions when the sections are applied to a brush, a pin carried by the projection on the body section and engaging through the handle of the brush and provided with a series of notches, the projection of the cover section having an opening to receive said pin, and a latch pivotally mounted on the projection of the cover section to engage any one of the notches of the pin, to hold the two projections clamped to the opposite edges of the handle of the brush.

3. The combination with a body section, of a cover section hingedly connected thereto, projections carried by the two sections and adapted to assume parallel positions when the sections are applied to a brush, a pin carried by the projection on the body section and engaging through the handle of the brush and provided with a series of notches, the projection of the cover section having an opening to receive said pin, and a latch pivotally mounted on the projection of the cover section to engage any one of the notches of the pin, to hold the two projections clamped to the opposite edges of the handle of the brush, said latch having a flange engageable with one edge of the projection on which the latch is mounted, to limit the latch in its engagement with the pin, and a flange on the opposite edge of the latch to be engaged by the finger and thumb for moving the latch.

In testimony whereof I hereunto affix my signature.

FRANK A. SEYMOUR.
